CLAIM

The ornamental design for a patient cable connector as shown and described.

DESCRIPTION

FIG. 1 is a top perspective view of a first embodiment of a patient cable connector;

FIG. 2 is a bottom perspective view thereof; and

FIG. 3 is a front view thereof.

The back, sides, top, and bottom surfaces of the first embodiment of the patient cable connector are unadorned and form no portion of the claimed design.

FIG. 4 is a top perspective view of a second embodiment of a patient cable connector;

FIG. 5 is a bottom perspective view thereof; and

FIG. 6 is a front view thereof.

The back, sides, top, and bottom surfaces of the second embodiment of the patient cable connector are unadorned and form no portion of the claimed design.

FIG. 7 is a top perspective view of a third embodiment of a patient cable connector;

FIG. 8 is a bottom perspective view thereof; and

FIG. 9 is a front view thereof.

The back, sides, top, and bottom surfaces of the third embodiment of the patient cable connector are unadorned and form no portion of the claimed design.

FIG. 10 is a top perspective view of a fourth embodiment of a patient cable connector;

FIG. 11 is a bottom perspective view thereof; and,

FIG. 12 is a front view thereof.

The back, sides, top, and bottom surfaces of the fourth embodiment of the patient cable connector are unadorned and form no portion of the claimed design.

The broken lines shown represent unclaimed subject matter and form no part of the claimed designs.
